DESIGN FOR A BRUSH

Heinrich Wechsler, New York, N. Y.

Application March 20, 1941, Serial No. 99,744

Term of patent 3½ years

To all whom it may concern:

Be it known that I, Heinrich Wechsler, a citizen of Germany, residing at 230 Fifth Avenue, New York, N. Y., in the county of New York and State of New York, have invented a new, original, and ornamental Design for Brushes, of which the following is a specification, reference being had to the accompanying drawing, forming part thereof.

The figure is a top perspective view of a brush showing my new design.

The other side of the brush not shown is substantially like the side shown.

I claim:

The ornamental design for a brush, substantially as shown and described.

HEINRICH WECHSLER.
